UNITED STATES PATENT OFFICE.

RICHARD D. MARTIN, OF EL RENO, OKLAHOMA.

PLANT FOR UTILIZING WASTE HEAT.

1,275,962.

Specification of Letters Patent. Patented Aug. 13, 1918.

Application filed June 20, 1917. Serial No. 175,786.

To all whom it may concern:

Be it known that I, RICHARD D. MARTIN, a citizen of the United States, and a resident of El Reno, in the county of Canadian 5 and State of Oklahoma, have invented a new and Improved Plant for Utilizing Waste Heat, of which the following is a full, clear, and exact description.

My invention relates to a steam plant 10 adapted to utilize the waste heat generated by coke ovens.

An object of the invention is to provide a simple, inexpensive and efficient plant which can be easily controlled and which 15 can be utilized in connection with the waste heat.

Another object of the invention is to provide a plant formed of a series of small steam units, each unit receiving the waste 20 heat from a series of coke ovens and where by any of the steam-plant units may be cut out without materially affecting the entire plant.

With the above and other objects in view, 25 the nature of which will more fully appear as the description proceeds, the invention consists in the novel construction, combination and arrangement of parts as herein fully described, illustrated and claimed.

30 In the accompanying drawings, forming part of the application, similar characters of reference indicate corresponding parts in all the views.

Figure 1 is a sectional elevation on line 35 1-1, Fig. 2, illustrating the main flue of a series of beehive coke ovens and a steam-plant unit associated therewith;

Fig. 2 is a plan view of a bank of beehive coke ovens and the steam-plant unit associated therewith, part of the top of the bank being broken out to show the main flue; and

40 Fig. 3 is an elevation of a bank of ovens showing the small steam boiler associated therewith and means for heating the boiler 45 independently of the coke ovens.

In the drawings, 4 is a coke-oven chamber provided with an outlet 5 in the dome carried through the dirt bed 6 covering the dome of the oven. A cover 7 is provided 50 for the discharge to the outlet 5 whereby the same may be maintained open or closed. Each of the series of ovens which is to supply heat to the steam-plant unit 8 is connected by an angling flue 9 extending from the outlet 55 of the oven to the main flue 10 running between the parallel rows of the ovens.

The steam-plant unit is preferably mounted on the bank of the ovens in close proximity to one of the faces of the bank, so that an independent fireplace 11 could be 60 provided for the boiler of the steam-plant unit between a pair of coke ovens, as shown in the drawings. This fireplace is connected to the main flue 10 by a flue section 12. The grate 13 for the fireplace 11 is accessible 65 through a fire door 14, and a draft door 15 leads to the ash pit. The two doors are maintained closed when the heat from the coke ovens is to be utilized for heating the 70 boiler 8. A suitable smokestack 16 is provided for the boiler to carry off the hot gases coming from the coke ovens to the boiler.

All the boilers or steam units of the plant 75 may be connected to a steam main 17 embedded in the dirt cover of the ovens, which dirt being hot will prevent condensation in the main. Each of the boilers is connected to the main by a suitably insulated conduit 18 extending from the steam dome 19 of the 80 boiler to the main.

The coke ovens may be operated in the usual manner by removing the cover 7 from the outlet 5 and leaving the fire doors of the boiler open. By closing the angling flues 85 9 at the outlet 5 by bricks or by a gate operable from the dirt bed, the coke ovens may be cut off from the boiler. In consequence, the same may remain idle with or without water without being damaged, as the gases 90 from the oven will not pass into the flues communicating with the boiler. On the other hand, when it is desired to cut a boiler into the steam plant it is maintained filled 95 with water, the fire box is closed, the angling flues are brought into communication with the outlets 5, and the covers 7 are put over the outlets. This operation, it will be noted, does not in any way affect the process of 100 coking the coal, as the operation of the oven is the same whether the cover is on or off the outlet 5.

Any type of boiler may be used and connected with as many ovens as necessary to obtain the desired amount of steam. As 105 previously pointed out, it is preferable to have the plant formed of a large number of small units, so that the cutting in or out of one or more of the units of the plant will not affect the entire plant materially. These 110 boilers may be set at any desired relative position to the coke ovens, as the type of

boiler and its position relative to the plant will have to be taken into consideration. Of course, the result will be the same.

I claim:

5. A plant for utilizing waste heat from coke ovens, comprising a bank of coke ovens arranged in two parallel rows, each oven having in its top a tubular neck closed by a cover, a main flue extending between the rows of ovens and in engagement with the several ovens intermediate their tops and bottoms, a curved branch flue for each oven, said flue leading from the neck of the oven below the cover thereof over the top of the 10 oven into the main flue, a steam generating unit mounted on the bank of ovens, a furnace having a flue and arranged below the
- 15

steam generating unit and between a pair of the ovens, and a flue leading from the main flue into the furnace flue.

20

2. A plant for utilizing waste heat from coke ovens, comprising a plurality of ovens arranged in parallel rows, each oven having in its top a tubular neck closed by a cover, a main flue extending between the rows of ovens, a branch flue for each oven, leading from the neck of the oven below its cover, to the main flue, a steam generating unit, a furnace having a flue and arranged below the said unit and between the outer portions of two ovens, and a flue leading from the main flue between the two said ovens into the furnace flue.
